CAR-TOP CAMPER

Jimmy M. Lambert, 1501 Tonawanda Drive,
Dothan, Ala. 36301

Filed Feb. 13, 1969, Ser. No. 15,761

Term of patent 14 years

Int. Cl. D12—14; D21—05
U.S. Cl. D14—27

FIG.1

FIG. 2

FIG. 1 is a view showing the front and one side of the car-top camper opened for use and attached to a car.

FIG. 2 is a view showing the back and the other side of the car-top camper opened for use as though attached to a car.

FIG. 3 shows the car-top camper, as folded with the hard-top portion acting as a cover, mounted on top of a car for traveling.

The elements shown in broken lines are included for illustrative purposes only.

I claim:

The ornamental design for a car-top camper, substantially as shown and described.
